UNITED STATES PATENT OFFICE.

JOUEL MARCUS SHACKELFORD, OF ASHLAND, KENTUCKY.

SASH-LOCK.

1,122,035.

Specification of Letters Patent. Patented Dec. 22, 1914.

Application filed July 3, 1914. Serial No. 843,861.

To all whom it may concern:

Be it known that I, JOUEL M. SHACKELFORD, a citizen of the United States, residing at Ashland, in the county of Boyd and State of Kentucky, have invented new and useful Improvements in Sash-Locks, of which the following is a specification.

This invention relates to improvements in window sash locks, proposing a device which may be operated to lock either or both of the sashes at any desired position along the window frame.

The object of the invention is to provide a sash lock of simple, inexpensive, and durable nature which may be readily applied to ordinary window constructions, entailing no departure from existing standards, which may be easily and quickly operated to lock or release either or both of the sashes, and, which acts positively in its locking function.

A sash lock in accordance with the invention includes a pair of rack or equivalent bars arranged respectively at one side of the window frame and at an adjoining side of one of the sashes, a pair of cog wheels disposed at substantial right angles to one another and mounted upon the sash which is devoid of a rack bar, and a pivotally mounted lock key arranged on the sash which carries the cog wheels and having projections which are operative by a single operation of said key to simultaneously engage between adjoining teeth of both cog wheels.

An embodiment of the invention is illustrated in the accompanying drawings, wherein:

Figure 1 is a view, partly in elevation and partly in section of a window structure to which the improved fastener is applied. Fig. 2 is a sectional view of the same in a plane at right angles to the elevation. Fig. 3 is a horizontal sectional view on the line 3-3 of Fig. 1 looking downwardly, and Fig. 4 is a detail perspective view of the locking key.

Similar characters of reference designate corresponding parts throughout the several views.

The letters A, B, and C designate, respectively, the lower sash, the upper sash, and the window frame in which said sashes are fitted. The upper sash is provided at one side thereof and on its inner face with a rack bar 1 and the frame C is provided at its side adjoining the rack-bar 1 and at the same elevation as said rack bar, with a

similar rack bar 2. The rack bars 1 and 2 are both coextensive in length with the sashes. The lower sash is provided on its upper face and at the corner thereof adjoining the rack bars 1 and 2 with a plate 3 provided with bearings 4 for spur wheels 5 and 6 respectively which are disposed at right angles, the spur wheel 5 co-operating with the rack bar 1, and the spur wheel 6 co-operating with the rack bar 2. The sash lock is completed by a locking key 7 which is in the form of a plate pivoted at 8 on the plate 3 and having at one end a finger piece 9 and at its other end an arcuate extension 10. The extension 10 is provided with lugs 11 and 12 arranged at an interval and angle corresponding to the interval and angular arrangement of the spur wheels 5 and 6, the lug 11 co-operating with the spur wheel 5 and the lug 12 co-operating with the spur wheel 6.

By moving the key 7 on its pivot to engage the lugs 11 and 12 between adjoining teeth of the respective spur wheels 5 and 6 the sashes will be locked against movement as is obvious. The key 7 may be operated in any position of either or both the sashes. Thus the lower sash may be raised to any desired elevation and locked therein by a manipulation of the key 7; or the upper sash may be lowered to any desired elevation and similarly locked; or the lower sash may be in any desired elevated position and the upper sash may be in any desired lowered positions and both sashes may be locked in their respective positions by a single operation of the key 7. When the key 7 is in locking or operative position it positively locks the sashes against movement whatever the positions thereof in the window pane.

To release the sashes the key 7 is moved from the dotted line position of said Fig. 3 to the full line position of said figure whereby to disengage the lugs 11 and 12 from the respective spur wheels 5 and 6 at which time either or both sashes may be freely moved to any desired position.

The lugs 11 and 12 are formed in cross section to correspond to the outline of the notches or recesses between the teeth of the spur wheels and their upper edges are preferably arranged on inclines whereby the lugs have a taper form and have a wedge fit between the adjoining teeth of the spur wheels. By thus forming said lugs the key 7 will

be frictionally retained in its operative or locking position and will not be liable to accidental displacement therefrom.

Having thus fully described my invention, I claim:

1. The combination with upper and lower sliding sashes and a frame inclosing said sashes of a pair of rack bars arranged at the same normal elevation, respectively, at one 10 side of said frame and at an adjoining side of one of said sashes, the rack bars being disposed in planes at right angles to one another, a pair of spur wheels carried by the other sash for engagement with the respective rack bars and also arranged in planes at right angles and a movably mounted key carried by said last named sash and having lugs arranged at an interval and angle corresponding to the interval and angle of the 15 spur wheels and formed to engage between adjoining teeth of the spur wheels.
2. The combination with upper and lower sliding sashes and a frame inclosing said sashes of a pair of rack bars arranged at the same normal elevation, respectively, at one 20 side of said frame and at adjoining side of one of said sashes, the rack bars being disposed in planes at right angles to one another, a pair of spur wheels carried by the other sash for engagement with the respective rack bars and also arranged in planes at right angles and a pivotally mounted key carried by said last named sash and having 25 lugs arranged at an interval and angle corresponding to the interval and angle of the spur wheels and formed to engage between adjoining teeth of the spur wheels.
3. The combination with upper and lower sliding sashes and a frame inclosing said sashes of a pair of rack bars arranged at the same normal elevation, respectively, at one 30 side of said frame and at an adjoining side of one of said sashes, the rack bars being disposed in planes at right angles to one another, a pair of spur wheels carried by the other sash for engagement with the respective rack bars and also arranged in planes at right angles to one another, a pivotally mounted key carried by said last named sash and having an arcuate portion provided with lugs arranged at an interval and angle corresponding to the interval and angle of the spur wheels and formed to engage between adjoining teeth of the spur wheels and an attachment plate having bearings for the spur wheels and on which the key is pivoted.

lugs arranged at an interval and angle corresponding to the interval and angle of the 35 spur wheels and formed to engage adjoining teeth of the spur wheels, the lugs having a tapered form whereby they engage between the teeth of the spur wheels with a wedge fit.

3. The combination with upper and lower 40 sliding sashes and a frame inclosing said sashes of a pair of rack bars arranged at the same normal elevation, respectively, at one side of said frame and at an adjoining side of one of said sashes, the rack bars being 45 disposed in planes at right angles to one another, a pair of spur wheels carried by the other sash for engagement with the respective rack bars and also arranged in planes at right angles to one another, a pivotally mounted key carried by said last named sash and having an arcuate portion provided with lugs arranged at an interval and angle corresponding to the interval and angle of the spur wheels and formed to engage between adjoining teeth of the spur wheels and an attachment plate having bearings for the spur wheels and on which the key is pivoted.

In testimony whereof I have hereunto set 60 my hand in presence of two subscribing witnesses:

JOUEL MARCUS SHACKELFORD.
